UNITED STATES PATENT OFFICE.

CHARLES E. GLESSNER, OF PORTLAND, OREGON.

FLYING MACHINE.

Application filed May 31, 1924. Serial No. 717,027.

To all whom it may concern:

Be it hereby known that I, CHARLES E. GLESSNER, a citizen of the United States, and a resident of Portland, in the county of 5 Multnomah and State of Oregon, have invented a new and useful Flying Machine, of which the following is a specification.

This invention relates more particularly to the art of aviation.

10 An object of my invention is to provide an exceedingly simple and efficient machine capable of rising vertically to the desired altitude and then flying in the desired direction.

15 A second object is to utilize the principles employed in airplanes for raising the machine vertically.

20 A third object is to provide a high degree of stability to the device and to so construct same that a minimum number of operators will be required.

25 A fourth object is to reduce the danger caused by the stalling of an engine.

I accomplish these results in the manner set forth in the following specification and as illustrated in the accompanying drawing, in which:—

30 Figure 1 is a plan of my device, Figure 2 is a section taken along the line 2—2 in Fig. 1. Figure 3 is a section taken along the line 3—3 in Fig. 1. Figure 4 is a plan of Fig. 3.

Similar numbers of reference refer to the same parts throughout the several views.

35 It will be understood that the drawings are largely diagrammatic and such small details as stays, fasteners, skin coverings to reduce resistance, detail structure of the airplane units, etc., have been omitted, owing to the small scale at which the drawings are made, and to their well known functions in the art of flying.

40 Referring in detail to the drawing, I have illustrated my device in its preferred embodiment in which it takes the form of a triangular trussed frame 10, in each of whose rounded vertexes is placed a turret 11 rotatably mounted in the circular guides 12. On each turret 11 is pivotally mounted an airplane 13 in the trunnions 14. Each airplane 13 is provided with the usual wings 15, propeller 16, rudder 17 and elevator 18. A skin 19 of suitable material may be employed to cover the frame 10.

45 In the center of the triangular frame 10 is placed a turntable, including an outer

ring 20 and an inner ring 21, preferably of channel trussed metal. The two rings 20 and 21 are joined together by means of the plate or lattice work 22. The plate 22 projects beyond the ring 20 and is used to fasten the brace wires 22^A and 22^B. The wires 22^C fasten to the lower leg of the ring 20. The outer ends of the wires 22^A, 22^B and 22^C are fastened to the trussed frame 10 after the fashion of a bicycle wheel.

50 Light rails 23 are placed on the inner sides of the channel-shaped rings 20 and 21 and support the flanged wheels 24 which are joined by the axle 25. From the axle 25 is suspended a post 26. There are preferably four sets or pairs of wheels 24 and four posts 26 whose lower ends 27 are adapted to rest upon the ground when the device 55 is not in flight.

55 Between the posts 26 is mounted a car 28 provided at its rear end with a rudder 29, which is broken away in Fig. 2. Suitable windows 30 are provided in the car 28.

60 It will be observed that the axles 25 of 60 the wheels 24 are tied together by a channel iron ring 31, which preferably extends completely around the turntable between the rings 20 and 21, and if desired may be supported at midway points by other wheels, if 65 it seems necessary.

65 I have also indicated a gas bag 32 for holding helium, or other buoyant gases, which bag may occupy the space in the frame 10 not occupied by the rings 20 and 70 21 and the turrets 11.

75 The operation of my device is as follows: When resting upon the ground in order to make the device rise in the air it is necessary to start the propellers on each of the 80 planes 13, and by manipulating the rudders 17 hold the position shown in dotted lines in Fig. 1, which is radial to the center of the frame 10. This action causes the frame 10 to rotate while the car 28 is resting on the ground. When sufficient speed has been attained by the planes they are directed upwardly by controlling their ailerons and elevators in the usual manner, causing the frame 10 to be lifted with same. When the 85 desired height is attained the planes are maneuvered around in the direction shown in full lines in Fig. 1, causing the entire device to move in the direction taken by all of the planes. In landing the operation is 90 reversed.

95 It is evident that should one or more of

100

105

110

the motors stall, that the plane will still act as a glider sustaining its portion of the weight, if not adding its propelling force for the time being. If this should occur 5 while the ascent is being made it is easily seen that the gyratory action of the frame 10 and its attached parts will prevent any bad effects.

In practice it may be found necessary to 10 employ additional propelled planes which may be mounted along the sides of the triangular frame 10 on turrets similar to those upon which the planes 13 are mounted. The additional planes may be either propelled 15 or mere gliders, as seems best, depending upon the type of machine being constructed.

While I have referred to the employment 20 of gas bags within the frame 10, it will be understood that this use is merely to offset 25 a portion of the weight of the frame, and is not intended to be sufficient to raise the device under ordinary circumstances.

The entire novelty in my device resides 26 in the employment of supporting planes for lifting purposes, in which the planes are confined to a circular orbit, giving a much better lifting action for the amount of power expended than is possible, for instance, 30 where a propeller is merely turned horizontally and driven at a high rate of speed, as is the common practice with machines now known as helicopters and gyroplanes.

Or, to restate the matter, the device gains 35 its increased lifting power from the great length of air base on which the planes can act. In other words, the air is not churned by the planes with which it comes in contact without having the opportunity to come to a state of comparative rest before being 40 again acted upon. This is further accented during climbing, in which the planes follow a helical path so that practically all of the air supporting the planes is new or undisturbed air.

I am aware that many forms of heavier- 45 than-air flying machines have been constructed in the past, I therefore do not claim such devices broadly, but I do intend to cover all such forms and modifications of 50 my device as fall within the appended claims, in which airplanes can be confined to a circular orbit in order to unite their lifting effect and to limit the area required to climb to the desired altitude—in other 55 words, by confining the travel of the planes to a helix to permit their rising or landing on a relatively small space of ground.

I claim:

1. In a flying machine, the combination

of a frame; three or more rotatable turrets 60 circumferentially mounted on said frame about its gyratory axis; and airplane units hinged on transverse axes on said turrets adapted to permit said planes to change 65 their vertical angles of flight.

2. In a flying machine, the combination of a flat frame; three or more rotatable turrets circumferentially mounted on said frame about its gyratory axis; airplane units hinged on transverse axes on said turrets 70 adapted to permit said planes to change only their vertical angles of flight; and a car supported by said frame.

3. A flying machine having, in combination, a triangular frame member; a plurality 75 of airplane units pivotally mounted on said frame member; and a car pivotally attached below said frame in a manner that said frame can be rotated without rotating said car.

4. A flying machine having, in combination, a trussed triangular frame; a turret formed at each vertex of said frame; an airplane unit hinged on each of said turrets; a turntable formed in the center of said 85 frame; and a car rigidly depending from said turntable.

5. A flying machine having, in combination, a trussed triangular frame; a turret formed at each vertex of said frame; an airplane unit hinged on each of said turrets; a turntable formed in the center of said frame; a car rigidly depending from said turntable; and means for controlling the angular position of said car in relation to said frame. 95

6. In a flying machine, the combination of a trussed triangular frame; an airplane unit pivotally hinged at each vertex of said frame; a turntable mounted in said frame; gas containers confined in said frame; a car 100 rigidly depending from said turntable; and rudder means on said car.

7. In a flying machine, the combination of a covered triangular frame with a plurality 105 of airplane units pivotally mounted over various parts of said frame, each of said planes being connected to said frame by means of a hinged pedestal which will permit said plane to change its fore and aft level but will hold its wings parallel to said frame; a turntable formed in said frame; a gas container occupying all of said frame not occupied by said turntable; and a car rigidly depending from said turntable adapted to lend stability to said flying machine. 115

CHARLES E. GLESSNER.
